UNITED STATES PATENT OFFICE.

ARTHUR J. TOWNSEND, OF CANTON, OHIO, ASSIGNOR TO THE NATIONAL PRESSED STEEL COMPANY, OF MASSILLON, OHIO, A CORPORATION OF OHIO.

SHEET-METAL-FORMING MACHINE.

1,292,158.

Specification of Letters Patent. Patented Jan. 21, 1919.

Application filed May 26, 1917. Serial No. 171,116.

To all whom it may concern:

Be it known that I, ARTHUR J. TOWNSEND, a citizen of the United States, residing at Canton, in the county of Stark and State of Ohio, have invented a new and useful Sheet-Metal-Forming Machine, of which the following is a specification.

This invention relates to sheet metal forming machines and is more especially designed 10 for bending sheet metal into the forms of metal lumber such as are in use at the present time, although the device is capable of use in forming sheet metal for various other purposes.

15 The object of the present invention is to provide a device of the character referred to for forming flanges upon the opposite edges of metal sheets or plates.

20 A further object is the provision of a device of this character which may be easily and readily adjusted for forming metal sheets into metal lumber of different widths.

25 A still further object is the provision of means for forming flanges of different widths upon the metal strips.

A still further object is the provision of a forming roll especially adapted for work of this nature.

With these objects in view the invention 30 consists in the novel construction and arrangement of parts, hereinafter described, illustrated in the accompanying drawings, and particularly pointed out in the appended claims, it being understood that various 35 changes in the form, proportions, size and minor details of construction may be made within the scope of the appended claims, without departing from the spirit or sacrificing any of the advantages of the invention.

40 In the accompanying drawings:

Figure 1 is a top plan view of a sheet metal forming machine embodying my invention.

45 Fig. 2 is a section on the line 2—2, Fig. 1. Fig. 3 is a section on the line 3—3, Fig. 1. Fig. 4 is a section on the line 4—4, Fig. 1. Fig. 5 is a section on the line 5—5, Fig. 1. Fig. 6 is a section through one of the 50 forming rolls.

Fig. 7 is an end view of a sheet before being passed through the machine.

Fig. 8 is an end view of the sheet after passing through the rolls shown in Fig. 2.

Fig. 9 is an end view of the sheet after being passed through the rolls shown in Fig. 3.

Fig. 10 is an end view of the sheet after being passed through the rolls shown in Fig. 4.

Fig. 11 is an end view of the finished sheet 60 after passing through the rolls shown in Fig. 5 and being ejected from the machine.

Similar numerals of reference indicate corresponding parts throughout the several figures of the drawings.

Referring more especially to the construction illustrated in the accompanying drawings, the numeral 1 indicates the base upon which the machine is mounted, said base being preferably rectangular in form as shown 70 in the drawings. The numerals 2 indicate bearings which are mounted upon suitable standards carried by the base 1, feed rolls such as indicated by the numeral 3 being journaled in said bearings, a drive pulley 4 75 being provided upon the shaft of one of the feed rolls in order to impart rotation thereto.

The device comprises essentially two parallel rows of brackets, each bracket carrying a pair of interfitting forming rolls, the 80 rolls upon each bracket being arranged to coöperate with the rolls upon the opposite bracket to form the two longitudinal edges of the sheet as the sheet is passed through the machine. For the purpose of adjusting 85 the forming rolls in order to accommodate sheets of various widths or to produce metal lumber of various widths all of the brackets upon one side of the machine are carried upon a table 5 which is mounted for slideable 90 movement upon the base 1 toward or away from the roll carrying brackets upon the opposite side of said base. The adjustment of this table is accomplished by means of the screws 6, said screws being threaded through 95 suitable bosses 7 formed upon the table 5, each screw being provided with an unthreaded portion 8, which is journaled through a suitable bearing 9 formed upon the base 1, set collars 10 being mounted upon said 100 screws adjacent each side of the bosses 9 to prevent lateral movement of the screws within the bearings 9. Each of the screws 6 is provided with a squared extremity 11 to

which a wrench or crank may be applied to rotate the screws in order to move the table 5 toward or away from the opposite forming rolls.

5 The machine shown in the drawings is designed to form metal lumber of the shape illustrated in Figs. 7 to 11 inclusive and this form of the machine comprises four sets of forming rolls through which the sheet 10 passes, each set of forming rolls comprising two pair of oppositely disposed interfitting rolls arranged to coöperate to form the two longitudinal edges of the sheet into the required shape as it passes between said rolls 15 but it will, of course, be understood that different changes in the position and arrangement of the rolls or in the number of rolls used may be made without departing from the spirit of the invention. The first 20 set of these forming rolls comprises the brackets 12 and 13 which are mounted **opposite to each other**, the bracket 12 being carried by the table 5 and the bracket 13 being permanently mounted upon the base 1. 25 Each of these brackets is provided with a lower bearing 14 which may be formed integral with the bracket and with an upper bearing 15 slidably mounted in a suitable groove in the upper extremity of the bracket, 30 an adjusting screw 16 being provided for adjusting said bearing with reference to the bearing 14. Short shafts 17 are journaled in the upper bearings 12 and 13 and carry rolls 18 and 19 respectively, said rolls being 35 of the greatest diameter at their centers and tapering away from the centers at each side as shown in the drawings. A gear wheel 20 is mounted upon each of the shafts 17 and meshes with a similar gear wheel 21 mounted 40 upon a suitable shaft located through the adjacent bearing 14 grooved rolls 22 being carried by said shafts and arranged to co-act with the upper rolls to form angular flanges 23 upon the longitudinal edges of the sheet 45 as it passes between said rolls as best shown in Figs. 2 and 8 of the drawings.

The next adjacent set of rolls is carried upon the oppositely disposed brackets 24 and 25, the bracket 24 being mounted upon 50 the table 5 and the bracket 25 permanently mounted upon the base 1. These brackets are preferably located at a different angle to the base from the brackets 12 and 13 for purposes hereinafter shown. The lower 55 bearings 26 are formed upon the brackets 24 and 25 and receive suitable shafts which carry the grooved rolls 27 and the gear wheels 28, the grooved faces of the rolls 27 being upon a different angle from the faces 60 of the rolls 22 in order to further bend the flanges upon the sheets as will be later described. The gears 29 mounted upon suitable shafts located through the slidable bearings 30 mesh with the gears 28, and the upper rolls 31 are carried upon said shafts, 65

said upper rolls being of suitable shape to interfit with the grooved rolls 27 in order to turn the flanges upon the longitudinal edges of the sheet at right angles as indicated at 32 in Figs. 3 and 9.

In Fig. 4 is shown the third set of rolls which are carried upon the oppositely disposed brackets 33 and 34 respectively, the bracket 33 being mounted upon a block 35 which is slidably mounted upon the table 5 and provided with slots 36 screws 37 or their equivalents being passed through said slots and into the table 5 in order to guide the block 35 as it is slidably moved upon the table 5. The brackets 33 and 34 are preferably disposed in the same angles as the brackets 12 and 13 of the first set of rolls. The bracket 34 is mounted upon a similar block 38 slidably mounted upon the base 1 and provided with slots 39 through which screws 40 are located, said screws being seated in the base 1 to guide the block as it is slidably moved upon said base. The brackets 33 and 34 are provided with the lower fixed bearings 41 in which are journaled the shafts of the grooved rolls 42 said shafts also carrying the gears 43 which mesh with the gears 44 mounted upon shafts of the upper rolls 45, said upper rolls being arranged to interfit with the grooved rolls. 95 The shafts of the upper rolls are mounted in the slidable bearings 46 in the same manner as the other upper rolls above described. This set of rolls is arranged to form the flanges 47 upon the longitudinal edges of the sheet as shown in Figs. 4 and 10.

The brackets 48 and 49 are mounted upon the blocks 35 and 38 respectively and are disposed in the same angles as the brackets 24 and 25. The lower bearings 50 are provided upon said brackets through which suitable shafts are journaled carrying the lower grooved rolls 51 and the gears 52, which gears mesh with the gears 53 mounted upon suitable shafts journaled in the adjustable bearings 54, the rolls 55 being mounted upon said shafts and arranged to interfit with the grooved rolls 51 in order to turn the flanges at right angles as indicated at 56 in Figs. 5 and 11 thus producing the finished metal lumber of a cross section best shown in Fig. 11.

For the purpose of adjusting the blocks 35 and 38 toward or away from the longitudinal center of the machine in unison these blocks 120 are provided with the internally screw threaded bosses 57 and 58 respectively, shafts 59 and 60, provided with screw threaded portions being located through said bosses. One extremity of the shaft 59 125 is journaled in a boss 61 formed upon the table 5, set collars 62 preventing any longitudinal movement of said shaft with relation to the table while the other extremity of said shaft is slidably mounted within a 130

boss 63 formed upon the base 1 and a pinion 64 is fixedly mounted upon said shaft intermediate the bosses 57 and 63. The shaft 60 is journaled in a boss 65 formed

5 upon the base 1, set collars 66 being provided upon said shaft to prevent lateral movement of the shaft with relation to the base and the other extremity of said shaft is journaled in a boss 67 formed upon the base.

10 An elongated pinion 68 is fixedly mounted upon said shaft and meshes with the pinion 64. The outer extremity of one of said shafts may be provided with a squared portion as indicated at 68 for the purpose of

15 applying a wrench or crank in order to rotate said shaft and through the pinions 64 and 68 the other shaft is rotated, thus moving the blocks 35 and 38 in unison toward or away from the longitudinal center of the

20 machine to form metal lumber of different widths and to form different width of flanges 56 upon said metal lumber.

The upper rolls of each set are preferably formed in the manner best shown in Fig. 6,

25 two conical disks 69 of any suitable steel or iron being connected together by means of screws 70, a comparatively thin disk 71 having a pointed or sharpened periphery 72 being placed between said disks 69, the disk

30 71 being formed of hardened tool steel or the like. By this construction it is not necessary to discard the entire roll when the edge thereof has become worn, the disk 71 being easily removed and replaced by a new disk.

35 Although the drawings and above specification disclose the best mode in which I have contemplated embodying my invention I desire to be not limited to the details of

40 such disclosure, for, in the further practical application of my invention, many changes in form and construction may be made, as

circumstances require or experience suggests, without departing from the spirit of the invention, within the scope of the appended claims.

I claim:—

1. A machine for forming sheet metal comprising a bed, a table adjustably mounted upon one side of said bed, a series of obliquely disposed brackets mounted upon said table, a second series of obliquely disposed brackets mounted upon said bed and parallel to the brackets upon said table, each of said brackets upon said bed being disposed opposite a bracket upon said table, each alternate pair of oppositely disposed brackets being of relatively greater incline and a pair of interfitting rolls carried by each of said brackets, the said rolls being disposed parallel to the brackets upon which they are carried and arranged to form the longitudinal edges of a sheet or strip of metal as it is passed through said machine.

2. In a machine for forming sheet metal comprising a bed, a table adjustably mounted upon one side of said bed, a series of obliquely disposed brackets mounted upon said table, a second series of obliquely disposed brackets mounted upon said bed and parallel to the brackets upon said table, each of said brackets carrying a pair of interfitting forming rolls, the lower roll upon each of said brackets being grooved and having the periphery of its inner portion disposed in a horizontal plane, said rolls being arranged to receive a sheet or strip of metal and gradually bend the metal into a desired form.

In testimony that I claim the above I have hereunto subscribed my name.

ARTHUR J. TOWNSEND.
